GUARD FOR HANGING ELECTRIC
LIGHT BULBS

Charles A. Scheeler, Buffalo, N. Y., assignor to
Buffalo Wire Works Co., Inc., Buffalo, N. Y.,
a corporation of New York

Application December 28, 1934, Serial No. 759,456

5 Claims. (Cl. 240—102)

This invention relates to a guard for hanging electric light bulbs and more particularly to such a guard which is adapted to be used in connection with an electric light bulb having a pendant bulbous portion and a gradually contracting neck extending upwardly from said bulbous portion; the guard being preferably made of wire and being supported on the bulb in such manner that it protects the bulb from 5 injury through an accidental blow. Such guards 10 are especially useful in factories.

Guards of various types have been designed for electric light bulbs but such guards have either been firmly attached to either the bulb 15 itself or to the socket which carries the bulb. This not only rendered such guards more expensive to construct and more difficult to apply, as compared with the present invention but the guard was also rigidly connected to the bulb so 20 that a blow striking the guard would be transmitted directly to the bulb and in many cases destroy the electrical filaments. The present invention provides a very simple and inexpensive guard which is easily applied to pendant bulbs 25 and is loosely supported around the contracting portion of the neck of the bulb with the center of the gravity of the guard as a whole below the support so that when the guard is struck 30 the entire guard tilts and absorbs the shock of the blow and then immediately falls back to its original position.

In the accompanying drawing:

Fig. 1 is a side elevation of a pendant electric light bulb showing a guard made in accordance 35 with my invention mounted thereon.

Fig. 2 is a top plan view of the guard and bulb shown in Fig. 1.

Fig. 3 is a view similar to Fig. 1 showing the manner in which the guard tilts when struck.

40 Fig. 4 is a perspective view of the guard shown in Figs. 1-3.

Fig. 5 is a view similar to Fig. 4 showing a modified form of my invention.

The guard embodied in my invention is 45 adapted for use in connection with a pendant or hanging electric light bulb which, as shown, comprises a pendant glass bulbous portion 10 and a gradually contracting neck extending upwardly from the bulbous portion and connected 50 to the usual screw plug or base 12 by means of which the electric light bulb is screwed into the usual socket.

The guard shown in Figs. 1-4 comprises a small ring 13 which, before the electric light 55 bulb is inserted in its socket, is slipped over the

neck 11 of the bulb so as to rest loosely on the contracting neck, as best shown in Fig. 1. Extending radially and horizontally from the small ring 13 are a plurality of horizontal arms 14, the outer ends of which are bent downwardly, as indicated at 15 and are connected to a large horizontal ring 16. The arms can be secured to the rings 13 and 16 in any suitable manner, as by welding or brazing and the ring 16 is substantially larger than the bulbous portion 10 of the 10 electric light bulb so that it forms a guard for the bulb. An essential feature of the invention is that the center of gravity of the guard, as a whole, is below the small ring 13.

The guard normally hangs loosely from the 15 neck of the electric light bulb in the horizontal position shown in Fig. 1. When the guard is accidentally struck, as by a blow against the large ring 16 or one of the arms, the guard tilts, the opposite side of the guard rising and lifting 20 the corresponding side of the small ring 13 from its seat on the neck 11 of the bulb, as best illustrated in Fig. 3. Immediately following the blow, of course, the guard falls back to the horizontal position shown in Fig. 1 and the small 25 ring 13 re-seats on the contracting neck 11 of the bulb in the same position which it took originally.

It will be appreciated that the invention is 30 subject to modification in form. For example, an additional ring or rings 17 can be used to connect the radiating arms so as to more completely protect the bulb against accidental injury. Such a modification is illustrated in Fig. 35 5 in which the other features of the guard are substantially similar to the form of the invention shown in Figs. 1-4 and therefore the same reference characters have been employed and distinguished from the preferred form of the invention by the suffix "a".

40 From the foregoing invention it will be seen that by loosely supporting the guard around the contracting part of the electric light bulb and by so forming the guard that its center of gravity is below its supporting part the guard 45 upon being struck yields and absorbs the shock of the blow instead of transmitting it to the bulb with possible injury to the filaments thereof. Following this the guard immediately resumes its original position. Therefore in a 50 factory having exposed bulbs guarded in accordance with my invention the guards are uniformly horizontal and are never knocked askew, such being common with ordinary guards and rendering 55 the appearance of the factory room unsightly.

to that extent. Further, it will be appreciated that a guard embodying my invention is very quickly and easily applied to an electric light bulb and is as easily removed and replaced when the bulb requires replacement.

I claim as my invention:

1. A guard for an electric light bulb having a pendant bulbous portion and a relatively thin, elongated contracting neck extending upwardly from said bulbous portion, comprising a support embracing an intermediate portion of said neck and loosely resting thereon and having line contact therewith and light skeleton guard means carried by said support and extending outwardly and downwardly therefrom and unconnected with said bulb, the center of gravity of the guard being below said supporting means whereby upon being struck, the guard tilts and temporarily lifts one side of said supporting means from its seat on said neck to which it returns by gravity following the blow.
2. A guard for an electric light bulb having a pendant bulbous portion and a relatively thin, elongated contracting neck extending upwardly from said bulbous portion, comprising a support embracing an intermediate portion of said neck and loosely resting thereon and having line contact therewith, light arms extending outwardly and downwardly from said support and carrying a light horizontal ring which surrounds said bulbous portion and is spaced a substantial distance therefrom, the center of gravity of the guard being below said supporting means whereby when the ring or arms of the guard are struck, said ring tilts and temporarily lifts one side of said supporting means from its seat on said neck to which it returns by gravity following the blow.
3. A guard for an electric light bulb having a pendant bulbous portion and a relatively thin, elongated contracting neck extending upwardly from said bulbous portion, comprising a support embracing an intermediate portion of said neck and loosely resting thereon and having line con-

tact therewith, light arms extending outwardly and downwardly from said support and carrying a plurality of vertically spaced light concentric rings which surround the bulb and are spaced therefrom, the center of gravity of the guard being below said supporting means whereby when the rings or arms of the guard are struck said rings tilt and one side of said supporting means is temporarily lifted from its seat on said neck to which it returns by gravity following the blow.

4. A guard for an electric light bulb having a pendant bulbous portion and a relatively thin, elongated contracting neck extending upwardly from said bulbous portion, comprising a wire ring embracing an intermediate portion of said neck and loosely resting thereon and in such form in cross section as to have line contact with said neck and light guard means carried by said support and extending outwardly and downwardly therefrom and unconnected with said bulb, the center of gravity of the guard being below said ring whereby upon being struck the guard tilts and temporarily lifts one side of said ring from its seat on said neck to which it returns by gravity following the blow.

5. A guard for an electric light bulb having a pendant bulbous portion and a relatively thin, elongated contracting neck extending upwardly from said bulbous portion, comprising a small wire ring embracing an intermediate portion of said neck and loosely resting thereon and of such form in cross section as to have line contact with said neck, wire arms extending outwardly and downwardly from said ring and carrying a large horizontal wire ring which surrounds said bulbous portion and is spaced a substantial distance therefrom, the center of gravity of the guard being below said small ring whereby when the large ring or arms of the guard are struck said large ring tilts and temporarily lifts one side of said small ring from its seat on said neck to which it returns by gravity following the blow.

CHARLES A. SCHEELER.
